UNITED STATES PATENT OFFICE

2,261,251

TRACTOR POWER SHOVEL

Charles V. Hallenbeck, Denver, Colo.

Application September 21, 1939, Serial No. 295,853

8 Claims. (Cl. 214—103)

This invention relates to an improved tractor power shovel.

As is well-known to those skilled in the art, the general outdoor construction work such as road-building, excavation, and the like, ordinarily requires moving large quantities of earth. Various types of power shovels have been developed for so moving earth and other material, particularly for the purpose of shoveling the material to be moved into a truck or other hauling means, whereby it is transported to another location where it is dumped.

As the work progresses, such equipment must be moved progressively and, in highway construction for instance, a power shovel is required to be moved over considerable distance. Furthermore, it may well occur that the space available in which a power shovel can operate is quite limited and there may be limiting factors interfering with the approach to the shovel, of the hauling units that are to transport the shoveled material.

Many common types of power shovels are too large to work in limited space and some of them are so heavy that their transportation from place to place presents difficulties. Again, in smaller construction projects, the common type of power shovel may represent too much expense in investment and operation to be economically practical.

Therefore, it is a principal object of this invention to construct a compact and efficient power shovel that is adapted to be carried on, transported by, and operated by a tractor.

Another object is the provision of a power shovel that readily can be used in a limited space and that requires no swinging boom.

A further object is to provide a power shovel that is light in weight and economically practical on either small or large construction projects.

Still another object is the provision of a power shovel that is universally adaptable to operation in difficult positions.

A further object is to provide a power shovel having a simplified system of control whereby the effort required to operate the shovel is minimized.

Other objects and advantages reside in details of design and construction which will be more fully disclosed in the following description and in the drawings wherein like parts have been similarly designated and in which:

Figure 1 is a plan view of a power shovel that embodies the present inventive concept;

Figure 2 is a side elevation looking in the direction of arrow 2 of Figure 1;

Figure 3 is a fragmentary sectional view along the line 3—3 of Figure 1 and drawn on a larger scale;

Figure 4 is a fragmentary sectional view taken along the line 4—4 of Figure 2; and

Figure 5 is a fragmentary sectional view drawn on a larger scale, illustrating a modified form of certain details shown in Figure 2.

In order to disclose an operable reduction to practice of the present inventive concept, reference will be had to the accompanying drawings which illustrate a typical example. Numerous changes may occur to those skilled in the art and it is therefore to be understood that the example herewith illustrated and described is not intended to express or imply any limitation to this invention, the scope of which is, in reality, measured by the appended claims.

The instant example comprises a frame structure designated as a whole by reference character 12, which is constructed and adapted to be carried upon a caterpillar-type tractor 13 through the intermediary of plates 14 on the tractor. The upper portion of the frame structure 12 includes an upwardly inclined track composed of rails 15, each of which is of channel-shape cross section as best shown in Figure 4. The rails 15 adjacent their upper ends bend downwardly in shovel-dumping loops 16. The rails 15 extend from their lower ends in front of the tractor, over said tractor, to the upper dumping loops 16 at the rear of the tractor.

A shovel 17 is carried upon a pair of shafts 18 having rollers 19 at their outer ends positioned to travel in the channels of the rails 15.

The lower ends of the rails 15 are bent downwardly and slightly back under the upwardly inclined portion thereof as shown at 15a. These downwardly and backwardly bent lower portions 15a of the rails 15 are therefore not perpendicular to the surface of the ground upon which the tractor bears, but they form an acute angle 45 with the surface of the earth in front of the frame.

A power take-off and winch assembly indicated at 20, is an integral part of the tractor 13 and is not illustrated in any great degree of particularity because it is not, per se, a part of this invention.

A cable 21 is attached to the drum 20a of the winch 20 in the usual manner, so that it may be wound thereupon by the power of the tractor 13. The cable 21 is reeved over an idler sheave

22, which is conveniently mounted upon the frame structure 12 and thence to a deep-groove sheave 23 to the hub of which it is anchored.

The sheave 23 is keyed to a shaft 24 which is journaled for rotation upon the frame structure 12 within the loops 16 of the track rails 15. The shaft 24 carries a pair of deep-groove sheaves 25 adjacent its outer extremities, to each of which is attached a shovel-actuating cable 26. The deep-groove sheaves 23 and 25 are of a type that wind their respective cables in a single tier of spiral formation so that the effective length of the respective lever arms of force as applied thereto or thereby, varies according to the number of turns of the respective cables wound thereon. The cables 26 which are attached to the deep-groove sheaves 25 are reeved over idler sheaves 27 and are attached to the shovel 17 as shown at 28.

The shovel 17 is provided with the usual wear-resisting digging teeth 29 and has a bottom 30 and a back plate 31 that preferably form an acute angle with each other, thus to provide a V-shaped material-carrying bucket. The particular advantages effected by the construction of the shovel 17 will be more fully set forth hereinafter.

Obviously, when cable 21 is wound upon drum 20a of the winch 20, said cable will be unwound from the sheave 23 and torque will be applied thereby to the shaft 24, the moments of force being transmitted from the cable 21 to shaft 24 through an effective lever arm that is relatively long because the sheave 23 is well filled with the turns of the cable 21 at the beginning of this operation.

Torque will be transmitted by shaft 24 to the sheaves 25, from which the cables 26 are well spent. Since there is but little cable on sheaves 25 at the beginning of this operation, power is transmitted to said cables 26 through an effective lever arm that is relatively short. Thus a highly advantageous power-transmitting ratio of lever arms is effected to wind the cables 26 upon sheaves 25, as a result of which the shovel 17 will be elevated along the rails 15 to the uppermost portions thereof, whence the shovel 17 will fall around the downwardly-turned loops 16 being thus turned to a dumping position.

Due to the V-shaped relationship of the bottom and back of the shovel 17, material therein is easily carried without spilling up along the rails 15 although as the shovel 17 traverses the upwardly inclined portions of said rails, the back portion of the shovel 17 will be below the normally bottom portion 30 of the shovel. As the shovel is completely inverted by the loops 16 of the rails 15, the material in the shovel is free to spill therefrom into a waiting truck or similar means of conveying the material to a desired location.

The advantageous ratio of the effective lever arms associated with the sheaves 23 and 25 as set forth, is of high importance because maximum lifting power is thus made available where it is particularly needed to fill the shovel with material, or in other words, cause the shovel to dig into the bank being excavated. This operation of digging the shovel into the bank of material to be excavated is called "teasing" the shovel and is accomplished by forward bodily movement of the shovel effected by a forward movement of the tractor 13, and at the same time, intermittently moving or jerking the shovel

slightly upward by means of the power takeoff winch and the associated cables.

For this operation, a maximum of lifting force is available because of the leverage ratio hereinbefore explained. This advantageous ratio is furthermore particularly effective in pulling the shovel full of material up around the bend of the rails 15 onto the upwardly inclined portion thereof. Obviously, a more direct lift is required in the beginning of the elevation of the shovel 17 than is required to move the shovel along the upwardly inclined portion of the rails. As the shovel approaches its upward dumping position, the ratio of the effective lever arms in the sheaves 23 and 25 becomes less advantageous for power but more advantageous for speed, which is an optimum operating characteristic.

Another highly important factor to facilitate loading the shovel or digging it into the bank being excavated, is the particular angular relationship of the lower ends 15a of the rails 15. Since these lower ends 15a of the rails form an acute angle with the surface of the earth, or in other words, with the direction of forward travel of the tractor 13, and since this angle is opposite to the general angle of inclination of the track, forward force applied to the shovel by forward movement of the tractor, or upward force applied by the cables, causes the shovel and its teeth to dig or crowd into the material being excavated, which is highly desirable.

One directional force applied to a shovel is not ordinarily entirely effective for loading the shovel, but such force should preferably be accompanied by the above set forth "teasing" of the shovel into the bank by jerking it upwardly slightly by means of the cables 26. This "teasing" action tends to cause the material in front of and above the shovel teeth to crack or break, permitting the shovel teeth, particularly when accompanied by the crowding effect, to penetrate further into the bank as the material loosens.

When the shovel full of material is at the upper dumping extremity of the rails 15, considerable backward tipping leverage is exerted upon the entire structure 12. Therefore, in order to prevent any tendency to tip up the frame structure 12 and the tractor 13, special provisions are made for supporting the back portion of said frame structure 12.

The rails 15 are not continuous members but each is composed of two separate members which are in close proximity as indicated at 32. The upper portions of the rails 15 are carried upon a piano-type hinge 33 so that as the shovel 17 loaded with material approaches the upper ends of the rails 15, said upper ends will hinge downwardly slightly. When no weight is on the upper ends of the rails 15, they are held in their normal position of alignment with the lower inclined portions of the rails 15 by means of structures shown best in Figures 2 and 4.

A cross member 34 is pivotally attached to the rails 15 therebeneath at 35 and is supported by means of a ball and socket joint 36 that bears upon a cross head 37 that is urged upwardly by compression springs 38. The cross head 37 is carried upon vertical supports 39 that extend downwardly through tubular members 40 that are part of the main frame structure 12.

At the lower ends of the vertical supports 39 just below the lower ends of the tubular structural members 40, shoes 41 are carried on said

supports 39. When no excess weight is on the upper ends of the rails 15, the springs 38 hold the supports 39 in an elevated position so that the shoes 41 are off the ground. When the shovel 17 loaded with material is pulled up towards its dumping position, the springs 38 are compressed until the shoes 41 bear upon the ground thus supporting the entire dumping end of the structure and preventing any tendency to tip the mechanism backward.

Since the surface of the ground on which the apparatus is operating is very likely to be rough or uneven, special provision is made whereby the shoe 41 on one side of the frame may find a footing at a different elevation from that of the shoe on the other side of the frame. To effect this compensation, the ball and socket joint 36 permits the cross head 37 to position itself at an angle from horizontal, which would be the result of one of the shoes 41 finding a bearing at an elevation different from that of the other shoe 41. To facilitate this positioning of the cross head 37, said cross head is provided with slip joints 42, which provide sufficient longitudinal and angular movement of the cross head 37 with reference to brackets 43 that connect said cross head with the supports 39.

Under some circumstances, it may be preferable to substitute wheels or rollers 44 shown in Figure 5, for the shoes 41. Wheels or rollers such as shown at 44, facilitate forward movement of the apparatus over uneven ground surface.

Obviously, the operator of this improved tractor shovel remains on the tractor and may control the entire operation from this position. A metal plate 45 is preferably placed on the upwardly inclined portions of the rails 15 immediately therebeneath to protect the operator and the tractor from any falling material that might accidentally be spilled out of the shovel as it, together with its load of material, is drawn upwardly over the tractor and the operator. Obviously, the protecting plate 45 is made in two sections as shown at 46, to permit the relative movement of the upper portion of the rails 15 with reference to the lower portions thereof as hereinbefore set forth.

In order to facilitate the return of the shovel 17 to its lowermost or digging position, after it has discharged its load of material, spring elements 47 are positioned on loops 16 of rails 15 where they will be contacted and compressed by the shovel 17 as it arrives at its dumping position.

After the shovel has been dumped and upon release of the cable 21, the spring elements 47 act by virtue of their stored energy, to move the empty shovel back around the loops 16 up onto the upper ends of the inclined portions of the rails 15 from where the bucket will traverse the inclined rails 15 downwardly by gravity under the control of the operator, as the cables 26 are spent from the sheaves 25.

While various types of return springs could be devised, the type herein illustrated in a spiral clock type having their free extremities 47a extending upwardly into the path of the shovel 17 as it approaches its dumping position. These means for returning the shovel to its lowermost or digging position are an important factor in the simplicity and efficiency of a tractor shovel built according to this invention.

Obviously, numerous changes in the details of construction may occur to those skilled in the art and may readily be made without departing

from this inventive concept. Briefly, the invention consists in providing a power shovel that is supported on a frame structure that is preferably adapted to be carried on a tractor, the frame structure having an inclined track over the tractor for positioning the shovel for digging in front of the tractor, and for elevating the shovel over said tractor for dumping at the rear of the tractor, together with a suitable system of cables advantageously arranged for actuating the movements of the shovel by power taken off the tractor, or power from any suitable source. Means for supporting the dumping end of the frame structure during dumping of the shovel are, under normal circumstances, advantageous, but such means may not always be essential. A definite advantage is gained by having a power cable attached to the hub of a sheave having a single deep groove and adapted to wind the cable in a single spiral tier, and having one or more other sheaves of similar construction for winding and spending shovel-actuating cables. However, one or more continuous cables connecting the winch with the shovel element and reeved over suitable idler sheaves readily could be used with the general structure herein disclosed.

Thus the stated objects of the invention are fully accomplished in that, as herein exemplified, a tractor power shovel built according to this invention is relatively small and compact, is easily transported, operates in a minimum of space, and shovels material in a highly efficient manner. It is highly universal in its field of usefulness, light in weight, and economical in investment, maintenance and operating costs. The effort required by the operator is reduced and the system of controls is highly simplified over devices of the prior art.

What I claim and desire to secure by Letters Patent is:

1. A power shovel comprising a frame structure having an upwardly inclined track, a shovel element positioned to move along said track from a lower digging position to an upper dumping position, and means for so moving the shovel element, said means comprising a power winch, a shaft journaled on the frame adjacent the upper end of said track, a deep-groove sheave mounted for driving the shaft, a cable connected with the sheave and with the winch, a pair of deep-groove driven sheaves secured to the shaft, and cables attached to the pair of sheaves and to the shovel.

2. A power shovel comprising a frame structure having an upwardly inclined track, terminating at its upper end in a downwardly ranging shovel-dumping portion, a shovel element positioned to move along said track from a lower digging position to an upper dumping position, means for so moving the shovel element, and resilient means for elevating the shovel along the said downwardly ranging portion adjacent the upper end of the inclined track for moving the shovel from a dumping position to a digging position.

3. A power shovel comprising a frame structure inclusive of an upwardly inclined track composed of upper and lower sections mounted for limited relative movement, spring means on the frame for supporting the upper section, means for supporting the upper section independently of the frame structure, a shovel element positioned to move along said track from a lower digging position to an upper dumping position, and means for so moving the shovel element,

4. A power shovel comprising a frame structure inclusive of an upwardly inclined track composed of a lower digging section and an upper dumping section mounted for limited relative movement, a crosshead mounted to support said upper section and for limited angular movement relative thereto, supports for opposite ends of the crosshead mounted on the frame for independent movement relative to said frame, spring means on the frame positioned to urge said supports upwardly, the lower extremities of said supports being positioned to engage the ground upon compression of the springs, a shovel element positioned to move along said track from a lower digging position to an upper dumping position, and means for so moving the shovel element.

5. A power shovel comprising a frame structure inclusive of an upwardly inclined track, a support for the track carried on the frame and movable with reference thereto, a compression spring on the frame positioned to urge said support upwardly, the lower extremity of said support being positioned to engage the ground upon compression of said spring, a shovel element positioned to move along said track, and means for so moving the shovel element.

6. In a power shovel inclusive of an upwardly inclined track, a shovel element positioned to move along said track and means for so moving the shovel element, the improvement which com-

5 prises a downwardly ranging 180° curved track portion positioned to facilitate dumping of the shovel element, and resilient means positioned adjacent said curved track portion to facilitate return of the shovel around the curve after dumping.

7. A power shovel comprising a frame structure inclusive of an upwardly inclined track, a support for the track carried on the frame and movable with reference thereto, a compression spring on the frame positioned to urge said support upwardly, a roller on the lower extremity of said support positioned to engage the ground upon compression of said spring, a shovel element positioned to move along said track, and means for so moving the shovel element.

8. A power shovel comprising a frame structure inclusive of an upwardly inclined sectional track one section of which is angularly movable with reference to the other section, resilient means positioned to support the relatively movable section independent of the frame structure, a shovel element positioned to move along said track, and means for so moving the shovel element, said resilient means for supporting the relatively movable section of the track being compressible by the weight of the loaded shovel passing along said track section.
